UNITED STATES PATENT OFFICE

2,116,225

VIBRATING SCREEN

Harry L. Strube, Philadelphia, Pa., assignor to
 Link-Belt Company, Chicago, Ill., a corpora-
 tion of Illinois

Application July 11, 1936, Serial No. 90,048

5 Claims. (Cl. 209—319)

My invention relates to an improvement in screens and has for one purpose the provision of an improved screen box or screen body member.

Another purpose is the provision of a screen box which includes a plurality of superposed box or screen elements, removably secured together, whereby a multiple deck screen may be assembled.

Another purpose is the provision of improved means for securing two superposed screen boxes together.

Other objects will appear from time to time in the course of the specification and claims.

I illustrate my invention more or less diagrammatically in the accompanying drawings wherein:

Figure 1 is a side elevation;

Figure 2 is an end elevation with parts in section; and

Figure 3 is a plan view with parts broken away.

Like parts are indicated by like symbols throughout the specification and drawings.

Referring to the drawings, I generally indicate any suitable base members or supports, herein indicated as the longitudinally extending wood beams which may be supported on any suitable uprights 2. Mounted upon each of the longitudinally extending base members 1, I illustrate brackets generally indicated as 3, each of which includes bottom abutting flanges 4 through which 30 pass securing bolts 5, and upright end portions 6 connected by a transverse portion 7, herein shown as parallel with and spaced from the members 1.

8 generally indicates a supporting leaf spring structure bolted to the bracket member 7 as by bolts 9. It is provided with recurved portions 10 terminating in reverse ends 11 parallel with the leaf spring body 8. These ends 11 are clamped between the clamp plates 12 and the brackets 13 40 as by the bolts 14.

The brackets 13 are secured in any suitable fashion to side frame members 20 of an upper screen box. The side frame members are shown at their lower edges as downwardly and inwardly 45 inclined as at 21. This extension is illustrated as integral but clearly a separate piece could be employed if desired. Brackets 22 are secured to the upper outwardly extending flange 20a of the side members 20 of the upper screen box which 50 are shown as outwardly flanged as at 23. Mounted in the brackets 22 is any suitable vibratory structure herein shown as a rotor shaft 24 carrying a pulley 25, preferably adjustable unbalanced members 26, and an eccentric portion 27. 28 is 55 any suitable housing connecting the brackets 22

and surrounding main extensions of the rotor. Any suitable transverse or cross members 30 are provided to connect the side frame members 20 of the screen box.

I may, for example, employ angle members, 5 some extending from side to side of the frame and others, as at 31, extending only part way across the screen frame. 32 indicate any suitable angle brackets, bolted thereto, which carry longitudinally extending supports 33 over which screen 10 cloth 34 may be tensioned. The cloth actually engages rubber covered portions or pads 35. 36 indicates any suitable horizontal shelf or flange upon which the edges of the screen cloth 34 are received. 37 indicates clamping members having 15 a lower flange 38 hooked into the edge of the screen cloth and an upper flange 39 opposed, as a tilting abutment, to the inner face of the side frame member 20.

40 indicates a screen tensioning bolt headed 20 as at 41 and extending through the member 37, and exteriorly through the side frame member 20. 42 is a wedge-shaped exterior abutment adapted to be engaged by a nut 43 or any other suitable means for drawing the lower flange 38 of 25 the member 37 inwardly toward the inner face of the side frame member 20, whereby to tension the screen cloth. The upper edge of the lower screen box member, as shown for example in Figure 2, is downwardly and inwardly inclined as at 30 50, in opposition to the outer lower face of the downward and inward extension 21 of the side frame member 20 of the upper screen box. The two parts may be secured together as by bolts 51.

As will be clear from Figure 2, assuming that 35 the upper screen box is mounted upon supporting springs 8, one or more lower screen boxes may be quickly and easily secured to or removed from it. All that is necessary is to oppose the portions 50 of the lower box to the portions 21 of the 40 upper box and then thread the bolts 51 through and tighten them up. The inclined portions 21 of the frame members 20 may all be apertured as at 52, in readiness for the addition of additional 45 screen boxes.

Whereas I have shown the supporting springs as secured to the upper of a pair of screen boxes, it will be understood that two or more additional screen boxes may be secured to the original one. It will be also understood that, with very slight 50 modification of the parts, the additional decks or boxes could be positioned above the screen box which is actually secured to the springs.

It will be realized that, whereas I have described and illustrated a practical and operative 55

device, nevertheless, many changes may be made in the size, shape, number and disposition of parts without departing from the spirit of my invention. I therefore wish my description and drawings to be taken as in a broad sense illustrative or diagrammatic, rather than as limiting me to the precise showing.

I claim:

1. In a vibratory screen, a screen box including a plurality of separable, superposed box members, a base for said screen, a flexible connection between said base and one of said box members, means for removably securing said box members together, including opposed downwardly and inwardly extending portions conforming to each other, one associated with the lower edge of the upper of two adjacent boxes, and the other associated with the upper edge of the lower of said two adjacent boxes, and means for securing said opposed portions together, said portions and securing means lying entirely within the periphery of the screen boxes.
2. In a screen box structure, a plurality of superposed separable screen boxes, each including side frame elements and connecting cross frame elements, the upper of each pair of adjacent screen boxes having associated with its side frame elements downwardly and inwardly inclined extensions thereof, the upper edges of the side frame elements of the screen next below having downwardly and inwardly inclined flanges in conformity therewith, and securing means for said opposed portions, said securing means and flanges lying entirely within the periphery of the screen boxes.
3. In a vibratory screen, a screen box having parallel side frame members, each said side frame member having an outwardly extending flange along its upper edge and an inwardly extending flange along its lower edge, vibrating means mounted on said upper flanges, an additional screen box having inwardly extending flanges opposed to the inwardly extending flanges of the first mentioned screen box, and means for securing said opposed inwardly extending flanges together, said flanges and securing means lying entirely within the peripheries of the screen boxes, a screen fabric mounted in the second screen box, means for holding the fabric in position, such means being located below and masked by the inwardly extending flanges.
4. In a vibratory screen, a screen box having parallel side frame members, each said side frame member having an outwardly extending flange along its upper edge and an inwardly extending flange along its lower edge, vibrating means mounted on said upper flanges, an additional screen box having inwardly extending flanges opposed to the inwardly extending flanges of the first mentioned screen box, and means for securing said opposed inwardly extending flanges together, said flanges and securing means lying entirely within the peripheries of the screen boxes, a screen fabric mounted in the second screen box, means for holding the fabric in position, such means being located below and masked by the inwardly extending flanges.
5. In a vibratory screen, a screen box having parallel side frame members, each said side frame member having an inwardly extending flange along its lower edge, an additional screen box having inwardly extending flanges opposed to the inwardly extending flanges of the first mentioned screen box, means for securing said opposed inwardly extending flanges together, screen mesh mounted on the lower screen box, and securing means therefor positioned beneath and vertically aligned with said inwardly extending flanges, a screen fabric mounted in the second screen box, means for holding the fabric in position, such means being located below and masked by the inwardly extending flanges.

HARRY L. STRUBE.
